Armin Elmendorf
By Chamberlain Brendenreich
Atty's

UNITED STATES PATENT OFFICE.

ARMIN ELMENDORE, OF CHICAGO, ILLINOIS, ASSIGNOR TO HASKELITE MANUFACTURING CORPORATION, A CORPORATION OF NEW YORK.

JOINT FOR METAL-SHEATHED RECEPTACLE AND THE LIKE.

Application filed May 23, 1921. Serial No. 471,926.

To all whom it may concern:

Be it known that I, ARMIN ELMENDORE, a citizen of the United States, residing at Chicago, county of Cook, State of Illinois, have invented a certain new and useful Improvement in Joint for Metal-Sheathed Receptacles and the like, and declare the following to be a full, clear, and exact description of the same, such as will enable others skilled in the art to which it pertains to make and use the same, reference being had to the accompanying drawings, which form a part of this specification.

My invention has for its object to produce a tight joint between elements of a structure as, for example, the body and cover or head of a box or barrel, made of metal-sheathed boards in a simple and effective manner.

The various features of novelty whereby my invention is characterized will herein-after be pointed out with particularity in the claims; but, for a full understanding of my invention and of its object and advantages, reference may be had to the following detailed description taken in connection with the accompanying drawing, wherein:

Figure 1 is a section through a fragment of a box or barrel and cover separated from each other, the parts being in their initial preformed condition;

Fig. 2 is a view similar to Fig. 1 illustrating the first step in the process of making the joint;

Fig. 3 is a view similar to Figs. 1 and 2, showing the joint completed;

Fig. 4 is a view similar to Fig. 1 showing a modification;

Fig. 5 is a view similar to Fig. 4 showing the joint completed;

Fig. 6 is a view similar to Fig. 5, illustrating an additional fastening means if one be desired;

Fig. 7 is a view similar to Figs. 1 and 4, showing a still further modification; and

Fig. 8 is a section showing the completed joint between the parts illustrated in Fig. 7.

Referring to the first three figures of the drawing, 1 represents the wall of a box or body or any other suitable wall made up of a board having on the exterior a metal sheathing, 2. The metal sheathing is extended beyond one end of the wall as indicated at 3. 4 is another wall adapted to lie against an edge of the wall 1 and be securely joined thereto;

the member 4 being a head or cover where the member 1 is a box or a barrel. The outer side of the wall 4 is covered with a metal sheathing, 5, projecting beyond the periphery of the same, as indicated at 6, 60 a distance equal to the height of the extension or flange, 3, less the thickness of the wall 4. The flange or extension, 6, is bent outwardly at right angles to the plane of the member 4 as illustrated in Fig. 2 so that 65 when the member 4 is set on the member 1 the flanges 3 and 6 engage with each other. Rivets, 7, pass through the flanges 3 and 6 to fasten them together and the double flange is then bent inwardly as indicated 70 in Fig. 3 so as to overlie the top of the member 4.

In the arrangement shown in Figs. 4 and 5 the sheathing on the member 1 is extended beyond the end of that member a distance 75 equal to the thickness of the cover member 4, as indicated at 8. The flange, 6, on the cover member is bent downwardly over the edge of the latter. Then when the members 1 and 4 are assembled as indicated in Fig. 80 5, the flanges 6 and 8 engage with each other. The joint may be sealed by placing a line of solder, 9, between the extreme upper end of the flange 8 and the base of the flange 6. If desired, greater mechanical 85 strength may be given to the joint by inserting nails or screws, 10, through the flanges 8 and 6 and into the body of the member 4.

In Figs. 7 and 8 I have illustrated an arrangement in which a still different type of 90 joint may be obtained. The member 1 with its flange 3 is the same as in Fig. 1. The co-operating wall or cover, 11, has a sheathing layer, 12, co-extensive with the same. The member 11 is set against the end of the member 1 within the flange 3 and the marginal portion of the latter which projects beyond the member 11 is then bent inwardly across the top of the latter as shown in Fig. 8. The joint may be sealed by means of a line of 95 solder as indicated at 13, while greater mechanical strength may be given to the joint by means of nails or screws, 14, passing inwardly through the inwardly-bent portion of the flange 3 and through the member 11 100 into the member 1.

It will be seen that a box or barrel made in accordance with the disclosure herein will have its joints tightly sealed, will present a wholly metallic exterior surface, and 110

may be assembled quickly and conveniently from parts suitably flanged in the course of manufacture thereof.

While I have illustrated and described only a few specific forms of my invention, I do not desire to be limited to the exact details thus illustrated and described; but intend to cover all forms and arrangements which come within the terms employed in the definitions of my invention constituting the appended claims.

I claim:

- 15 1. A structure made up of a metal-sheathed wall and a second wall having a face overlying an edge of the former, in which the metal sheathing of the first wall extends outwardly across the end of the other wall.
- 20 2. In a structure of the character described, two walls each sheathed with metal on the exterior thereof, said walls being arranged at an angle to each other, one of said walls lying upon an edge of the latter wall,

the sheathing on the latter wall being extended beyond the same past the end of the other wall.

3. In a structure of the character described, two walls each sheathed with metal on the exterior thereof, said walls being arranged at an angle to each other, one of said walls lying upon an edge of the latter wall, 30 the sheathing on the latter wall being extended beyond the same and engaging the sheathing on the other wall.

4. In a structure of the character described, two walls each sheathed with metal on the exterior thereof, said walls being arranged at an angle to each other, one of said walls lying upon an edge of the latter wall, the sheathing on each of said walls being 40 continued beyond the ends of the same in the form of flanges contacting with each other.

In testimony whereof, I sign this specification.

ARMIN ELMENDORF.
